CLAIM

The ornamental design for a breath analyzer, as shown and described.

DESCRIPTION

FIG. 1 is a perspective view of a design for a breath analyzer;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of the design for a breath analyzer of FIG. 1 in which an end portion of the housing is in an extended state;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken lines depict environmental subject matter only and form no part of the claimed design.
